UNITED STATES PATENT OFFICE.

SAMUEL HY. CROCKER, OF LONDON, ENGLAND.

PEN.

SPECIFICATION forming part of Letters Patent No. 703,549, dated July 1, 1902.

Application filed March 22, 1900. Renewed February 5, 1902. Serial No. 92,748. (No model.)

To all whom it may concern:

Be it known that I, SAMUEL HY. CROCKER, engineer, a subject of the Queen of Great Britain and Ireland, residing at 31 Furnival street, Holborn, London, England, have invented certain new and useful Improvements in Pens, of which the following is a specification.

This invention provides a pen which can be easily detached from the penholder even when fouled with ink. With the pens and penholders commonly in use it is very difficult to remove the pen or nib from the holder after it has been used for some time, as the parts adhere together, owing to a deposit of dry ink, frequently causing great inconvenience and soiling the fingers of the person using the pen. Such pens are usually slid into the holder, which is provided with means for retaining them in position.

My improved pen instead of being secured inside of the holder is fitted on the outer side and is clipped into position by a motion at right angles to the holder. The pen or nib is formed at or near its upper end with an extension at each side, which continues the curve of the nib through the greater part of a circle. These extensions or wings are resili- 25 ent and spring onto the tubular holder, clipping it tightly, so that the nib is securely held in position. The edges of the wings are sufficiently distant from each other to allow them to open when pressed over the surface of the holder, so that they slide over it and on passing 30 the half-circle close together to grip the holder. To detach the pen, all that is required is to push the writing end up, the other end of the pen acting as a fulcrum, so that the wings slide over the surface of the holder and are opened by it until they pass 35 the widest portion, when the nib is released.

The accompanying drawings illustrate my invention.

Figure 1 is a perspective view of the pen 45 in position. Fig. 2 shows it separate. Fig. 3 illustrates the method of removing the pen, and Fig. 4 shows a slight modification.

The holder A consists simply of a tube

fitted onto the end of a handle, or the usual form of holder may be employed. As the nib or pen B is fixed to the outside of the holder, the metal tube or ring may be made very much smaller than the ordinary ferrule, so that a saving of metal is obtained as well as simplicity in making. The pen is formed 55 with the wings C shown close to the upper end and continuing the curve of the stem, the gap between the wings being of sufficient width to enable the pen to be sprung over the holder. The pen may of course also be 60 slid onto the holder to take up the same position; but it is easier to clip it on in the manner described.

Fig. 3 shows the pen partly removed, and it may be seen that the upper end bears upon 65 the surface of the ferrule, while the wings are forced over it. The wings or clipping portions, which are of course resilient, may extend along the whole straight length of the pen; but I prefer to make them short and 70 at the upper end only.

Instead of wing-pieces at both sides of the pen a single extension A' at one side might serve the same purpose, as in the form shown in Fig. 4.

What I claim as my invention, and desire 75 to secure by Letters Patent, is—

1. A pen stamped from one piece of metal, having a portion of its stem extended at the side in such a manner that it can be clipped 80 sidewise onto the outer surface of the penholder, substantially as described.

2. A pen, stamped from one piece of metal, having at the upper end of its stem two projecting wing-pieces continuing the curve of 85 the stem through the greater part of a circle, and adapted to be clipped sidewise onto the outside of a penholder, substantially as described and shown and for the purposes 90 specified.

In witness whereof I have set my hand in the presence of two witnesses.

SAM'L HY. CROCKER.

In presence of—

FRANK WILLIAM PATTISON,
JOHN FRANCIS GAIRNS.
